M. S. FROST.

Car Brake.

No. 15,038.

Patented June 3, 1856.

UNITED STATES PATENT OFFICE.

MAHLON S. FROST, OF DETROIT, MICHIGAN.

RAILROAD-CAR BRAKE.

Specification of Letters Patent No. 15,038, dated June 3, 1856.

To all whom it may concern:

Be it known that I, MAHLON S. FROST, of the city of Detroit, county of Wayne, State of Michigan, have invented a new and useful Improvement in Self-Acting Continuous or Through Brakes for Railway-Cars; and I do hereby declare that the following is a full, clear, and exact description of the construction and operation of the same, reference being had to the annexed drawings, making part of this specification, in which—

Figure 1 is a longitudinal elevation and Fig. 2 a ground plan as shown in a tender and passenger car.

15 The nature of my invention consists in an arrangement of transverse slide blocks on the end of the tender platform, operated by the engineer so as to engage as desired, a system of bumper rods simultaneously with 20 a system of traction rods throughout a train, whereby the brake may be applied both by the crowding together of the cars, or by any tendency of same to separate; the engagement from car to car being effected 25 by similar transverse sliding blocks at each end of the cars, operated by lever connection with the said bumper and traction rods; the said rods being used together or separately as desired.

30 The levers A A' stand on the forward part of the tender to the right and left of it. The right lever connecting with the rod B is used in all ordinary application of the brakes. The left lever connecting with the 35 rod B' is used only for extraordinary emergencies or when the speed of the train is required to be diminished suddenly, and when the train is backing. The other lever when the train is going ahead. Its operation is as 40 follows. The levers A and A' on being thrown backward move the elbows C and C' by means of the rods B and B'. These elbows again connecting by rods with the sliding blocks D and D' move these sliding 45 blocks opposite to the ends of the rods E and E'. These rods E and E' connecting with the cross-bars F and F' move the rods E and E' on the other end of the car. The rods E and E' are attached by toggle joints 50 to the levers L L which apply the brakes in the ordinary mode, but the balance beams o o o o o are joined together, or drawn toward each other by the rods H H H H H H. The ends of these rods H pass through 55 the balance-beams o and through the elliptical springs K K K K K K which regulate

the pressure or power applied against the wheels. This is done by these springs being made so as to yield under a given power on the rods H. The sliding rods E and E' also connect by toggle joints j and j' with the lever M and M'. These levers M and M' are bent around the common center P P and by means of the levers M' and M''' connect with the sliding block N and N'. 60 65

The operation of this invention is as follows. When the levers A and A' are vertical the sliding blocks D and D' remaining in the position as shown in the draft, are not brought in contact with the rods E and E' but allow these rods to pass forward and backward under the tender as the cars approach or recede from it and no action whatever is produced upon the brakes. 70

The engine driver on starting or leaving 75 the station at the commencement of his trip, throws back the lever A and allows it to remain in that position during the remainder of the trip. This position of the lever A places the sliding blocks D opposite the end 80 of the sliding rod E so that whenever the engine driver shuts off his steam the speed of the engine being reduced, the momentum of the cars brings them together, and the rod E coming in contact with the sliding 85 block D, is moved back carrying with it the lever L and applies the brakes to the wheels, and by means of the levers M and M' shifts the sliding block N, on the forward part of the car, opposite to the rod E in the tender, 90 and the block N, on the back end of the car, opposite the rod E in the following car, and so on throughout the train, the spiral spring r bringing the rod E back to its 95 place as soon as the power is off. This appliance of the brakes is all that is required to reduce the speed on all ordinary occasions, where the train stops at regular stations, or has room to reduce its speed gradually. The position of the block D 100 once made serves throughout the remainder of the trip, without further care or attention on the part of the engine driver. Should however an obstacle present itself upon the road, or any other emergency arise 105 requiring the sudden and prompt action of the brakes that should reduce the speed of the train as rapidly as possible, the engine driver throws back the lever A'. This moves the sliding block D' sufficiently to 110 permit the hooked end of the rod E' to catch on the forward end of the said block.

The momentum of the cars bringing the end of the rod E against the sliding block D, the brakes are applied as before stated. The momentum of the cars being overcome 5 by the action of the brakes sooner than that of the locomotive, they separate and the brakes would be relieved until the locomotive and cars could again be brought together, but the hooked end of the rod E' by 10 catching on the forward end of the block D' holds the brakes to their work. The other end of the rod E' attaching through an intermediate cross-bar F' with the cross-bar F which connects with the brakes 15 as before described. The cross-bar F' lies below the cross-bar F turning upon the same center G. The cross-bar F is provided with a pin R against which the cross-bar F' strikes carrying with it the cross-bar F 20 which operates the brakes. Also by means of the levers M'' and M''' the sliding blocks N' is moved in position for the hooked end of the rod E' on the following car to catch, and so on throughout the train, all the cars 25 being provided in the same manner. Thus the steady application of the brakes is maintained, whether the cars are closing or separating and the speed promptly reduced.

In case the cars have not space enough 30 between them to admit of the working of the rods E and E' to a sufficient distance to apply the brakes efficiently, I provide an intermediate lever—as shown by the blue dotted line in the tender—T. This lever T 35 is attached at one end to the rod E and at the other end to the lever L and turns upon the point u which is nearest to the rod E so that when the rod E is pushed back and with it the first end of the lever T the other 40 end of the same moves the lever L forward to a greater distance—in proportion as the

point u is nearest to the rod—so that the sliding rods E are not required to move so far as in the other arrangement in order to operate the brakes. This arrangement 45 would place the lever L at the other end of the trucks because it is moved in the opposite direction from what it is in the other mode of attachment. It is shown only in the tender of the draft and model but would 50 operate in the same manner throughout the train.

I do not lay down any particular manner of putting on the sliding blocks, nor any definite distance between the rods E and E' 55 nor designate the strength of the machinery. These will be arranged as the construction and size of the cars upon which they are placed may make it most convenient or necessary, and can be judged of by any good 60 mechanic. The brakes may also be worked in the usual manner by hand, the brake wheel and shaft w being attached by a rod to one end of the cross bar F or by any other convenient mode.

Having thus fully described my machinery and the manner of using it, what I claim as new therein, and desire to secure by Letters Patent is the following, viz:

The arrangement of the sliding blocks 70 D D' and N N' at the ends of the car platform for engaging and operating simultaneously a set of through bumper and traction rods for applying the brakes, the said sliding blocks being under the control of 75 the engineer, and capable of acting upon both sets of rods, or either separately as may be desired.

MAHLON S. FROST.
